UNITED STATES PATENT OFFICE.

EMILY TAYLOR ALLISON, OF NEW YORK, N. Y.

BOTTLE-CAP REMOVER.

1,150,160.

Patented Aug. 17, 1915.

Application filed March 2, 1914. Serial No. 322,101.

To all whom it may concern:

Be it known that I, EMILY TAYLOR ALLISON, a citizen of the United States, and resident of the borough of Brooklyn, county 5 of Kings, city and State of New York, have invented certain new and useful Improvements in Bottle-Cap Removers, of which the following is a specification, reference being had to the accompanying drawings.

10 The invention relates to removers for bottle-caps of the type known as crown corks, which are usually made to seal the bottle by being forced over the top thereof and crimped at the lower edge beneath a rim or ledge at the top of the bottle. Great difficulty and much inconvenience has often attended the removal of caps of this nature, especially as the extractors for such purpose have been devices entirely separated from 15 the bottle and often lost or out of place when most needed. This inconvenience has been most frequently experienced in homes and among families to whom the bottled beverages so capped or sealed have been 20 supplied.

25 The object of the invention is to produce a simple and effective bottle cap remover the utility of which depends largely upon its permanent connection with the bottle 30 and the facility with which it may be operated.

35 The improvement consists of a wire encircling the neck of the bottle below the head thereof and forming pivotal bearings or fulcrums for wire lever arms and a handle by which the same may be operated, as hereinafter described and pointed out in the claims.

40 In the drawings Figure 1, is a side elevation of a bottle neck with a cap seal thereon and of the remover at rest or in the normal position which it would occupy with respect to the bottle neck. Fig. 2, is a side elevation of the same showing the handle 45 swung out from the bottle neck and the lever arms acting on the cap so as to displace and remove it. Fig. 3, is a front elevation of a bottle neck sealed as in Fig. 1, with the cap remover in its normal position.

50 Fig. 4, is a cross sectional plan taken on the line 4, 4, of Fig. 2, disclosing more plainly the formation of the encircling wire and its pivotal bearings for the lever arms which appear in section.

55 In these drawings *a*, represents the bottle neck and *b*, the crown cork or cap. The

remover *c*, is preferably formed of wire with a looped end *c*², which has a slight outward turn as seen in Fig. 1, to admit of easy operation. The wire *c*, is formed so as to rest against the bottle neck between the looped end *c*², and the shoulders or corners *c*', of the lever arms which take a turn so as to straddle the neck of the bottle and another turn which continues to the end where 60 eyes *c*³, *c*³, are formed for the purpose of fulcrumming.

65 The encircling wire *d*, may be doubled at its center so as to form a pivotal bearing *d*', for one of the eyes *c*³, and then made to pass 70 around the bottle neck beneath the head thereof, and the two ends are then drawn together or twisted so as to form a pivotal bearing *d*², for the other eye *c*³, of the other lever arm *c*'. The wiring of the bottle neck 75 so as to provide the pivotal bearings for the lever connections is very simple and can readily be done by machine. The remover proper is not difficult to make and the whole attachment of the parts to the neck of the 80 bottle may be done very cheaply. The member *c* is preferably formed of spring wire. As the portions thereof between *c*' and *c*³ are shaped to fit the bottle neck, it is obvious that the remover will normally lie in the 85 position shown in Figs. 1 and 3, and that it can only be placed in the position shown in Fig. 2 against the tension of the spring wire. It is thus evident that my improved 90 cap remover is adapted to be used on bottles which are washed and filled by machinery, as the cap remover will not open up and prevent the passage of the bottle through the machine.

95 The act of removing the bottle cap simply requires an outward pull or pressure which swings the lever arms up over the bottle head and the shoulders *c*', *c*', are brought into direct contact with the lower or crimped edge of the cap which is thereby 100 lifted and tipped, and it may be readily shoved off and removed in a convenient and quick manner.

Having thus described my invention, what I claim as new and desire to secure by 105 Letters Patent is:—

110 1. A bottle cap remover comprising an element encircling a bottle neck and provided with laterally projecting fulcrums on opposite sides of the bottle neck, and an element comprising a spring wire member having its ends fulcrumed in said laterally pro-

jecting bearings, the portions of said second named member intermediate its middle portion and its end portions being adapted to form bearing portions, which, when in operation, are forced against a bottle cap to remove the same.

2. A bottle cap remover comprising an element encircling a bottle neck and provided with laterally projecting fulcrums on opposite sides of the bottle neck, and an element comprising a spring wire member having its ends fulcrumed in said laterally projecting bearings, the portions of said second named member intermediate its mid-

dle portion and its end portions being 15 adapted to form bearing portions, which, when in operation, are forced against a bottle cap to remove the same; and the portions of said second named member between said bearing portions and said fulcrumed 20 portions being bent to partially encircle said bottle neck, whereby when in its normal position said second named member is adapted to be held close to said bottle neck.

EMILY TAYLOR ALLISON.
